UNITED STATES PATENT OFFICE.

MICHAEL A. BARBER, OF NORWICH, CONNECTICUT, AND ANDREW WIGGIN AND WILLIAM SOAR, OF BOSTON, MASSACHUSETTS, ASSIGNORS TO JOHN W. FREE, OF BOSTON, MASSACHUSETTS.

MALT GROWING AND DRYING APPARATUS.

SPECIFICATION forming part of Letters Patent No. 393,202, dated November 20, 1888.

Application filed November 11, 1887. Serial No. 254,881. (No model.)

To all whom it may concern:

Be it known that we, MICHAEL A. BARBER, of Norwich, in the county of New London and State of Connecticut, and ANDREW WIGGIN and WILLIAM SOAR, both of Boston, in the county of Suffolk and State of Massachusetts, all citizens of the United States, have invented a new and useful Improvement in Malt Growing and Drying Apparatus, of which the following is a full, clear, and exact description, reference being had to the accompanying drawings, forming a part of this specification, in explaining its nature.

The invention is an improvement upon that described in Patent No. 351,491 to James O. Brown and John W. Free, dated October 26, 1886; and it relates especially to the mechanism or devices for stirring and agitating the malt upon the floors of the various chambers used in practicing the process, or in as many of them as it may be desired to use.

In the drawings, Figure 1 is a view of a portion of a malt-chamber, representing a portion of the floor of the chamber, the turning-buckets, their arrangement in relation to each other and to the center upon which they are adapted to be moved. Fig. 2 is a view in vertical section of a casing of a chamber and in elevation of the buckets and their operating devices. Fig. 3 is a view, part in vertical section, taken through one of the buckets, and part in elevation of the mechanism shown in Fig. 2. Fig. 4 is a diagram to illustrate the operation of the buckets due to their oblique position, to which reference will hereinafter be made. Fig. 5 is a detail view of the frame or hanger.

Referring to the drawings, A represents a section of the wall of a malting-chamber which is cylindrical in form. a represents the floor, which is perforated throughout, as represented by the section a', one perforated section only of the floor being shown in Fig. 1.

B is a vertical shaft, preferably centrally located in relation to the malting-chamber A. To it is secured a bracket or frame, C, which supports the shaft c, upon which the buckets D are mounted, and also the devices for rotating it. The shaft c is so arranged that it is ob-

lique or at an acute angle to a radial line extending from the center of the vertical shaft B to the outer end of the said shaft c, and the latter is supported at its inner end by a box, c', carried by an arm of the frame C, and upon which the box preferably is adjustable or movable in order to vary the obliquity of the angle of the shaft.

The oblique arrangement of the shaft c is illustrated by the diagram Fig. 4, in which the dotted line x denotes a radial line drawn from the center of the shaft B to the outer end of the shaft c, or the radius of the circular chamber, and the full line x' denotes the oblique line at an acute angle to the radial line, on which we prefer to arrange the shaft c.

The outer end, c', of the shaft has a bearing in the hanger c', extending downward from the horizontal bar c', forming a part of the frame C, and extending from the inner part of the frame substantially parallel with the shaft c. This arm c' has secured to its under surface at or near its outer end an anti-friction roll, c'', which bears upon the rail or support c'', which extends about the malting-chamber A', close to or in contact with the wall thereof.

The frame C also has the arm c' and the stay-rod c'', running from the end of the arm to the end of the bar c'. (See Figs. 1 and 2.) The frame C is turned with the shaft B, to which it is secured, to cause the buckets D to be moved horizontally over the floor of the malting-room upon a circular path. The shaft c is rotated to turn the buckets while they are being moved over the floor. The shaft c is set and the buckets shaped so as to bring the edge of the lifting-blades upon the same line and so as to just clear the floor a, and the buckets vary in the extent of their lifting capacity, the inner bucket having the least and the outer bucket the greatest. This is produced by providing the inner bucket with a less number of lifting-blades d than the outer buckets; and we prefer that the intermediate buckets also be graded in the same way, so that the outermost buckets shall have the greatest lifting capacity, the next in number will have less, the third still less, and the fourth or inner one the least.

The reason for varying the capacity of the

buckets is because the malt or grain is by the advancing movement of the buckets, as a whole, caused to be thrown or moved to some extent from the center outwardly, making the malt or grain gradually increase in depth from the center to the wall of the chamber.

The shaft B is rotated slowly by means of a worm-wheel, b, and the worm b' upon the shaft b². The bucket-shaft c is rotated by means of a sprocket-wheel, b³, upon the inner end of the shaft, the sprocket-wheel b⁴ upon a short shaft mounted upon the frame C and secured to the bevel-gear b⁵, and the sprocket-chain b⁶. The sprocket-wheel b⁴ and its bevel-gear b⁵ are driven by the bevel-gear b⁷ upon a short tubular shaft having a bearing upon the shaft B, a second bevel-gear, b⁸, upon said tubular shaft, and a bevel-gear, b⁹, upon the horizontal shaft b¹⁰. (See Figs. 1 and 3.)

There may be used for moving the grain or malt from the ends of the end buckets into the path of the same the guiding-plates E E', the first of which is attached to the hanger c¹ and is shaped and bent so that its front edge is in front of the front edge of the buckets, and also bears against the inner edge of the wall or of the rail c⁶, and serves to move the grain from the wall inwardly sufficiently to bring it in front of the outer bucket, and the plate E' is attached to the frame C between the inner bucket and the sprocket-wheel and acts in a similar way in relation to the inner bucket.

By hanging or supporting the buckets obliquely, as distinguished from a radial line from the center of the shaft B, we have ascertained that the grain or malt is more uniformly lifted by the buckets and distributed or dumped than if they were arranged radially in relation to the shaft B. The blades of the buckets may have any suitable shape, and we prefer the curved shape illustrated in Fig. 3.

The operation of the apparatus is as follows: The grain or malt is fed to the chamber A', covering the floor thereof to the depth of a number of inches, and when desired, for the purpose of assisting in the malting process, the mass of grain or malt is stirred, broken up, and separated by the movement of the buckets through the mass. The buckets advancing in a line and rotating lift the grain or malt from the floor of the chamber in comparatively small quantities, and by lifting-blades which deposit it in a broken separated condition and in a new relation to the rest of the malt and to the floor of the machine. This changing of the mass continues so long as it may be desired. The apparatus may be used in connection with all the various stages of the treatment of the grain. By varying the location and capacity of the buckets and the number of their blades it enables each lifting-blade to do the same amount of work. We have ascertained, also, that the grain or malt is given centrifugal or centripetal motion on the floor, according as the buckets are arranged upon a radial line or upon a line which is oblique to such radial line, and that midway between the

extremes—that is, between the radial line and the extreme oblique line—there is a position of the buckets that is a neutral one, and which enables them to take the grain or malt without moving it on the floor, so far as this centrifugal or centripetal motion of the malt is concerned, and as a rule we desire that the buckets and shaft should be hung or supported in this neutral relation to the shaft B, and when so hung or supported the malt or grain, as the buckets are moved in their circular path, can be by their rotation upon their supporting-shaft taken up and dumped on the same path, finding and leaving it level and evenly distributed, and not crowding the grain or malt away from or toward the center of the machine.

Having thus fully described our invention, we claim and desire to secure by Letters Patent of the United States—

1. In a malting apparatus, the combination, with a circular chamber, of a vertical operating-shaft at or near the center of said chamber, a horizontal malt agitating or stirring shaft extending from near the center of said chamber outward and arranged obliquely relative to the radius of said chamber, or to a radial line extending from the center of said vertical shaft to the outer end of said horizontal shaft, a series of turning-buckets carried by said horizontal shaft, and means for imparting rotary and progressive movements to said horizontal shaft, substantially as set forth.

2. In a malting apparatus, the combination, with the circular chamber, of a vertical operating-shaft at or near the center thereof, a horizontal shaft extending from near the center of said chamber outward and arranged obliquely relative to the radius of said chamber, or to a radial line extending from the center of said vertical shaft to the outer end of said horizontal shaft, a graded series of turning-buckets carried by said horizontal shaft, the outermost bucket having the greatest number of turning-blades and the innermost bucket the least number thereof, and means for imparting rotary and progressive movements to said horizontal shaft, substantially as set forth.

3. In a malting apparatus, the combination, with a circular chamber, of a vertical shaft, B, at or near the center thereof, the frame C, secured to said shaft B and provided with the box c' and with the horizontal bar c⁴, the hanger c³ at the outer end of said bar, the shaft c, journaled in said box and arranged obliquely relative to the radius of said chamber, a series of malt-turning buckets carried by said shaft c, and means for rotating the latter to operate said buckets, substantially as set forth.

4. In a malting apparatus, the combination, with a circular chamber, of a vertical shaft, B, at or near the center thereof, the frame C, secured to said shaft and provided with the box c' and the bar c⁴, the hanger c³ near the outer end of said bar, the bucket-carrying shaft c, journaled in said box and hanger, the sprocket-wheel b³, fixed to said shaft, the sprocket-wheel

b^4 , supported by said frame, the chain b^6 , connecting said sprocket-wheels, and means for operating said sprocket-wheel b^4 , substantially as set forth.

5. In a malting apparatus, the combination, with a circular chamber, of a vertical shaft, B, at or near the center thereof, the frame C, secured to said shaft and having the horizontal bar c^4 , provided with the hanger c^3 , the guiding-plate E, attached to said hanger, the guiding-plate E', attached to said frame C, the horizontal bucket-carrying shaft c , journaled in said frame and hanger, and means for imparting rotary and progressive movements to said shaft, substantially as set forth.

10. 6. The combination, with the circular chamber A, having the circular rail or support c^6 ,

of the vertical shaft B, the frame C, secured to said shaft and having the horizontal bar c^4 , provided with the hanger c^3 and anti-friction roll c^5 , the horizontal bucket-carrying shaft journaled in said frame and hanger, the sprocket-wheels b^3 and b^4 , the former attached to said shaft c , the chain connecting said sprocket-wheels, the bevel-gears b^5 , b^7 , and b^8 , to operate said sprocket-wheel b^4 , and driving mechanism for the said gear b^8 and for the said shaft B, substantially as set forth. 25
